CONDUCTOR RAIL SUPPORT

Johan L. Harmsen, 68 Hawkridge Ave.,
Markham, Ontario, Canada

Filed Oct. 7, 1968, Ser. No. 13,854

Term of patent 14 years

Int. Cl. D8—03

U.S. Cl. D8—235

FIG. 1

FIG. 2

FIG. 3

FIG. 4

FIG. 5

FIG. 6

FIGURE 1 is a perspective view of a conductor rail support, showing my new design;

FIGURE 2 is a side elevational view thereof, the other side being substantially identical;

FIGURE 3 is an end elevational view thereof;

FIGURE 4 is a perspective view of a modified form of another conductor rail support embodying my new design;

FIGURE 5 is a side elevational view thereof, the other side being substantially identical; and

FIGURE 6 is an end elevational view thereof.

I claim:

The ornamental design for a conductor rail support, as shown and described.
